UNITED STATES PATENT OFFICE

MICHEL JAVICK, OF PLAINS, PENNSYLVANIA

DESIGN FOR A WALL ORNAMENT

Application filed March 29, 1932. Serial No. 43,322. Term of patent 3½ years.

To all whom it may concern:

Be it known that I, MICHEL JAVICK, a citizen of the United States, residing at Plains, in the county of Luzerne, and the State of Pennsylvania, have invented a new, original, and ornamental Design for Wall Ornament, of which the following is a specification, reference being had to the accompanying drawing, forming part thereof.

The figure is a perspective view of the wall ornament, showing my new design.

I claim:

The ornamental design for a wall ornament, as shown.

MICHEL JAVICK.
